B. SAPIENZA

TELEPHONE CALL REGISTER

Filed March 7, 1922

INVENTOR
B. Sapienza

BY *J. L. Laramore* ATTORNEY

UNITED STATES PATENT OFFICE.

BENEDETTO SAPIENZA, OF NEW YORK, N. Y.

TELEPHONE-CALL REGISTER.

Application filed March 7, 1922. Serial No. 541,748.

To all whom it may concern:

Be it known that I, BENEDETTO SAPIENZA, a citizen of the United States, residing at New York, in the county of New York and State of New York, have invented certain new and useful Improvements in Telephone-Call Registers, of which the following is a specification.

This invention relates to call registering apparatus and is designed to be used in conjunction with a telephone set. The principal object of the device is to provide an apparatus which will give a visible indication of the number of telephone calls which have

been received during the absence of the person who is authorized to receive such calls.

The above and other objects will become apparent in the description below in which like characters of reference refer to the like-named parts in the drawing.

Referring briefly to the drawings, Figure 1 indicates a top plan view of the apparatus with a part of the casing torn away to expose the mechanism within.

Figure 2 represents a sectional side elevational view of the same and is taken on the line 2-2 of Figure 1.

Figure 3 is a similar sectional view taken on the line 3-3 of Figure 1.

Figure 4 is a diagrammatic representation of a telephone set with the registering apparatus connected thereto on an auxiliary circuit.

Describing the drawing more in detail and taking the wiring diagram into consideration, as represented in Figure 4, the numeral 10 indicates a transmitter and 11 a receiver of a common type of telephone which is universally used for the conveyance of the sound waves. Both transmitter and receiver are connected in parallel to the main lead wires 12 and 13. The usual primary and secondary induction coils 14 and 15 respectively, together with a receiver hook 16, a condenser 17 and a ringer 18 are all installed in the circuit in proper relation to one another and are well-known to those skilled in the art. As the apparatus requires no change in the wiring of the telephone set, the function, use and description of the latter has been obviously treated with brevity taking into consideration and enumerating the most essential members only, for the proper identification thereof.

The register is connected in series to a

wire 19 which is tapped off from the ringer circuit and has its opposite end 20 grounded. This auxiliary circuit to which the apparatus is connected, is completed by a wire 21, one end 22 being grounded while the other end joins the main lead wire 12. Said wire 21 is provided with a battery 23 for energizing the auxiliary circuit and cutout switch 24.

The register is connected in series to the auxiliary circuit and essentially comprises a rectangular hollow casing in the corners of which are formed lug 26 by which the device can be secured to a wall. The underside of the casing is entirely open and has a cover plate 27 secured thereon in a suitable manner. A spindle member 28 journalled in the wall of said casing, projects rearward so that the pointed end thereof is rotatably received in a pivot bearing 29 fixed to the rear plate 27. The exterior projecting end of the spindle 28 has a knurled thumb knob 30 which is provided for rotation of the spindle for the purpose of resetting the dial after the latter has been rotated.

Spindle 28 has a dial 31 secured thereto adjacent the wall 25^a of the casing. A radially formed orifice 32 in the casing wall exposes the dial face 33 to view so that the numerals 34 on said face can be read thru the orifice from an appreciable distance.

An annular disk 35 fixedly mounted on spindle 28 adjacent to the dial, has a plurality of equally spaced notches 36 which are engaged by a lever 37 pivoted at 38. This lever 37 has a downwardly extending angular arm 39 having a slot which engages a pin 40 fixed to a plunger 41. Said plunger is slidable within the core of an electromagnet 42 and has a tapered head 43 at one end which is adapted to engage the notches 36 on the disk 35, when the lever 37 has been released from one of the notches thru the action of the electro-magnet. A spring 44 engaging the lever 37 urges the latter downwardly into engagement with the disk.

A spiral spring 45 between the plate and the disk has its outer end secured to the latter by a screw 46 and the inner end is secured to the pivot bearing 29. This spring is provided for rotating the disk for a purpose which will be more fully hereinafter described.

In use the apparatus is first set so that the

zero on face 33 of the dial 31 is visible thru the orifice 32. As the switch located at the central station and designated by 24 is closed, ringer 18 will signal that a call is waiting 5 to be answered. The auxiliary circuit formed by wires 12, 19 and 21 is simultaneously closed, thus energizing the electromagnet 42 which slides the plunger 41 in the direction of the disc. In so doing lever 37 is 10 rotated out of engagement with the notch 36 permitting the spring to rotate the dial in a counter clockwise direction. The plunger head 43 will engage the nearest notch and check the rotation of the said dial centrally 15 of its travel, so as to prevent the dial from receiving uncontrollable momentum, and also to permit rotation to the next number only, irrespective of the time the electromagnet remains energized. Obviously, as each 20 additional call is received the operation is repeated, and the total number thereof will be registered by the numeral showing thru the orifice 32. When the number of calls received has been noted, dial 31 is rotated 25 or reset by rotating the knurled thumb knob 30 until the zero numeral appears visible thru the orifice 32, after which the apparatus is prepared to register additional calls.

The person to whom the telephone calls 30 have been sent, during his absence will see at a glance the number of calls received. It should be understood that the central station has inquired and received the call numbers of the persons who have phoned so that when 35 the absent person returns each of the phone numbers can be obtained by asking for same at the central station.

I claim:

1. A call telephone register comprising a casing, a spindle rotatable in said casing, a numbered dial, and a notched disk secured to said spindle, a pivoted lever engaging the notches having an angularly extending arm, an electromagnet, a plunger slidable in said electro-magnet, said plunger being connected with and adapted to release the lever from engagement with the notches of said disks to permit rotation of the same, upon its forward movement, the end of said plunger making contact with the periphery 50 of said disc, and means for rotating the dial upon the release of said disc.

2. A call telephone register comprising a casing member, a spindle rotatable in said casing, a dial and notched disk mounted thereon, a pivoted lever having a detent engageable with the notches of said disk, an angularly extending arm on said lever, a spiral spring having its outer end secured to the disk and its inner end fixed to the spindle bearing, said spring being adapted to rotate said disk when released by the lever, an electro-magnet, a plunger slidable in the electro-magnet loosely engaging the lever arm, said electro-magnet being adapted to 60 actuate the lever and disengage the same from the notches of said disk when the electro-magnet is energized, and a point on said plunger adapted to ride on the periphery of said disk and engage in the notches therein 70 when in a forward position.

In witness whereof I affix my signature.

BENEDETTO SAPIENZA.
